Specification of Letters Patent.

Patented Sept. 1, 1914.

Application filed October 24, 1912. Serial No. 727,569.

To all whom it may concern:

Be it known that I, JOHN H. C. ALEXANDER, a subject of the King of Great Britain, residing at Oakland, in the county of Alameda and State of California, have invented new and useful Improvements in Propellers, of which the following is a specification.

My invention relates to screw propellers in a general way but more particularly of 10 the helix form which are employed for various purposes, such as, for instance, windmills, fans, vessels, flying machines, etc., and consists in providing a general form for constructing the blades thereof, whereby the 15 greatest possible amount of the energy absorbed by the propeller is imparted to the fluid or medium in which the propeller works, in such a way as to produce the useful result for which the propeller is intended 20 and designed.

In the construction of propellers it is obvious that, to secure the results that I have specified above, the form of the blade must bear at all points such definite relationship 25 to its velocity at such points that the fluid or medium which is acted upon or to which motion is imparted by the surface of the blade shall have equal velocity relative to the axis of the propeller in any plane normal to such 30 axis throughout all parts of the column of said fluid, etc. In other words, there should be no relative motion between parts of the column in the same plane normal to the axis of rotation of the propeller; and the fluid or 35 medium acted upon or to which the motion is imparted must, in order to fulfil these conditions, leave the propeller in one direction only and with the same velocity throughout its entire body relative to the axis of the propeller.

It must further be evident that, in order to avoid a loss in efficiency, the portion of the blade which first acts upon the fluid or medium acted upon or to be set in motion by 45 the propeller, or through which the propeller is to progress, must be so formed and at such an angle to a plane normal to its axis as to offer the least practicable resistance to its entrance and produce the least practicable instantaneous acceleration and that 50 this angle must be so modified from the advancing edge to the trailing edge of the blade, as to produce a gradual acceleration of the fluid or medium acted upon and that 55 this modification must be such that the ef-

fective pitch of the blade at any circular cross section concentric with the propeller axis shall equal the whole pitch of the propeller divided by the angular width of the blade at that section. Again, it is evident 60 that if said column is to leave the propeller in one direction only and that this direction is to be such as to utilize the power absorbed by the propeller to the utmost, the form of the blade on any plane normal to the axis of 65 revolution of the propeller must be such as to prevent centrifugal action by the propeller and both this form and the form of the blade at all sections parallel to the axis of rotation are embodied in my invention and 70 the nature, characteristic features and scope of same will be readily understood from the drawing herewith and forming a part hereof. I have sought to secure the greatest 75 possible clearness in showing my meaning and intention by illustrating the methods of production of the actual form of my invention as though it had no volume, i. e., no actual thickness of material, excepting where, for the sake of clearness, I have indicated an 80 actual hub designated N. Since the dynamic efficiency of the propeller is not dependent upon, nor is my invention concerned with, any other feature than the form thereof, since also the thickness of the various elements of any propeller would vary with 85 each variation in size or other conditions to be met with in practice and since the form of the back of the blade in an actual propeller, designed on the lines prescribed by my invention, would be exactly similar to the form of the front of the blade as I have shown it, excepting the variations necessary to permit the inclusion of the material of construction 90 between the two surfaces of the blade and 95 what variation might be necessary to give the edges of the blade the best form for reducing resistance to the medium in which the blade is to operate, all of which variation should, as far as possible, be made in the 100 form of the surface of the back of the blade excepting only the necessary filleting or reinforcing, added to the blade where it joins the hub, which may be on either or both sides.

In the accompanying one sheet of drawing Figure 1, is a plan view of the propeller constructed according to my invention; Fig. 2, is a vertical elevation taken on dotted line y, y of Fig. 1; and Fig. 3, is 110

a view showing the increasing pitch curve assumed by the blade at cross sections, to wit, s to t , u to v , and w to x .

Referring to Fig. 1, it will be seen that the blade may be formed either by the arc of a circle as indicated by the dotted line and indication of any selected radius r , on the advancing edge of element L or any suitable curve as, for instance, the one used for the advancing edges indicated by the solid lines on elements K or L, which curve is part of a logarithmic spiral, the essential requirement, whatever form is used, being that, in the event that a curve is used, any point on the advancing edge shall have greater angular advance in the direction in which the propeller rotates, when using the front or more unmodified surface of the blade to act upon the fluid or medium to be acted upon or passed through, which direction of rotations I shall hereafter call the normal one in contradistinction to the reverse or backing direction, than any other point between it and the hub of the propeller, *i. e.*, that there shall be an increase in the angular advance from hub to tip and that whatever form is used, the peripheral tip of the advancing edge, if produced to the peripheral circle, shall have greater angular advance, in the normal direction of rotation than any other portions of the blade.

The method of producing the form of the blade elements in the propeller, as shown particularly on Fig. 1, is as follows:—Having decided upon the form to be used for the advancing edge of the blade element, the pitch of the propeller and the angular width of the blade element, the axial travel of the generatrix in forming the surface of one blade element will be to the pitch of the propeller as the angular width of the blade is to 360 degrees. Having determined this dimension it is to be divided into any convenient number of parts, the only consideration being that there shall be enough such divisions as to produce sufficient accuracy in the form of the curve of the surface of the blade between the trailing and advancing edges.

The peripheral circle is laid out to any scale and element K is produced by dividing an arc of the peripheral circle equal in length to the angular width of the blade element into as many parts as has been decided upon, as above mentioned, to accurately produce the curve in the blade element between the trailing and advancing edges. In this instance, the number so taken is eight.

The divisions are not equal but are a series in geometrical progression starting at the trailing edge of the blade element, so as to

produce an increasing axial pitch from the advancing to the trailing edge of the blade; thus, $a-b$ will be the first term and $h-i$ the last term of the series, and the common multiplier used will be such as to produce the best curve which experience dictates and will vary with the medium to be acted upon by the propeller. The points, a, b, c, d, e, f, g, h , and i having been located on the peripheral circle are now joined to the center of the peripheral circle by the lines and angle or angles or by the arc or curve selected as the form of the advancing edge of the blade element, as shown, and the plan of the blade element viewed parallel to the axis of the propeller is now complete. Any section can now be produced by the usual method of projection, as shown on Figs. 2 and 3. The lines 1, 2, 3, 4, 5, 6, 7, 8 and 9, on Fig. 2, being equidistant parallel lines separated by such intervals that the total distance between lines 1 and 9 to the scale used in the figure bears the same ratio to the total pitch of the propeller to be designed, to the same scale, from the propeller form as the angular width of the blade element bears to 360 degrees, and is equal to the axial travel of the generatrix to the scale used, in forming one surface of one blade element.

After the propeller is completed as above described, the edges may be rounded off or otherwise shaped to present any desired outline, without affecting the efficiency of the blade form, except in so far as it decreases the blade area.

It is to be understood that my use of the word "blade" does not limit my invention to propellers having one blade, but simply refers to one of any number of blades which may be used and which will all be similar in all respects to the blade described.

Believing I have produced novel and useful improvements in this class of inventions, and having thus described the same to be understood and practised by those skilled in the art to which the same appertains, what I claim is—

An impeller having one or more blades, each blade having the form described by a generatrix forming part of a logarithmic spiral diverging from the axis to the periphery of the blade and entirely in advance of the radius which moves in a plane normal to the axis and sweeping the blade, and describing a helix of increasing axial pitch.

In testimony that I claim the foregoing I have hereto set my hand this 19th day of October, 1912.

JOHN H. C. ALEXANDER.
